NEWSPAPER VENDING MACHINE

Lee S. Wallington, 1204 N. Linden St., Bloomington, Ill.

Filed Mar. 18, 1960, Ser. No. 15,923

3 Claims. (Cl. 221—194)

My invention relates to a new and useful improvement in a newspaper vending machine and more particularly to a vending machine for vending newspapers one at a time upon actuation of a vending door of such machine.

An object of my invention is in the provision in a machine of this character of a manually operated means for vending newspapers.

Another object of my invention is in the provision in a machine of this character of a means for vending a single newspaper from a magazine of vertically stacked newspapers.

A further object of my invention is in the provision in a machine of this character of an arrangement of parts for advancing the follower of the magazine into a paper stack supporting position with respect to the remaining newspapers in the magazine after each vending operation of the machine.

Yet another object of my invention is in the provision in a machine of this character of an arrangement of parts for retracting the newspaper follower from its stack supporting position with respect to the newspapers in the magazine during the vending operation thereof.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the cabinet in which my vending machine is contained;

Fig. 2 is a side elevational detailed sectional view taken on line 2—2 of Fig. 6;

Fig. 3 is a side elevational detailed sectional view taken on line 3—3 of Fig. 6;

Fig. 4 is a fragmentary perspective view of the rear sprocket wheel retracting mechanism as associated with my machine;

Fig. 5 is a fragmentary perspective view similar to Fig. 4 but showing the parts in actuated retracting position; and

Fig. 6 is a top plan view of the interior of the cabinet of my vending machine.

My invention relates to a newspaper vending machine and comprises a cabinet 10 having a locked hinged cover 11 and a front wall 12. The front wall 12 has formed therein a discharge opening 13 through which the newspapers are vended. A hinged door 14 normally closes the opening 13 and in a manner hereinafter described is instrumental in actuating the vending operation of my vending machine. The door 14 comprises an arcuated back wall 15 and a top finger grip 16. The back wall 15 terminates into laterally extending end wing plates 17 which are pivotally connected as at 18 to end plates 19 provided by the front wall 12 at either end of the opening 13. The arrangement is such that the door 14 is mounted for pivotal movement about a horizontal axis in an anti-clockwise direction as seen in Figs. 1 and 2. The open-

2

ing 13 has extending therein in front of the door 14 a stationary discharge plate 20 extending between the end wing plates 17 of the door 14 and over which the newspapers pass when vended.

Within the cabinet 10 there is provided a newspaper magazine consisting of a front retaining wall 21, side walls 22 and 23 and a movable follower 24. Extending rearwardly from the front retaining wall 21 and in a lower horizontal plane with respect thereto is a series of spaced apart parallelly extending paper supporting tracks 25. The movable follower 24 is adapted to pass over the tracks 25 as it is moved relative to the front retaining wall 21 in a manner hereinafter described.

The front retaining wall 21 provides a downwardly inclined chute 26 which extends in the direction of the opening 13 between the end plates 19 and terminates rearwardly of the door 14 as seen in Figs. 2 and 3.

Beneath and beyond the outermost tracks 25 is a pair of spaced apart parallelly extending supporting members 27. Connecting the opposite corresponding ends of the supporting members 27 is a pair of rotatably carried shafts 28 and 29. The shaft 28 is so disposed as to extend in a spaced parallel direction with respect to the front retaining wall 21. The shaft 28 on opposite ends thereof 25 rotatably carries sprocket wheels 30. The shaft 29 rotatably carries on opposite ends thereof a retracting mechanism 31. This retracting mechanism 31 includes as a part thereof sprocket wheels 32. Adapted to be passed about the sprocket wheels 30 and 32 are driving chains 33. It is to these driving chains 33 that the follower 24 is fixedly attached as at 34.

Also carried by the shaft 28 and rotatable therewith is a flat coil spring 35. This spring 35 has its one end connected at 36 to the underside of a portion of the follower 24. The normal coiled tension of the spring 35 causes the follower 24 as well as the chains 33 to move in one direction toward the stationary front retaining wall 21.

As viewed in Figs. 2 and 3 there are provided adjacent either end of the front retaining wall 21 supporting plates 37. These supporting plates 37 have on their outer surfaces actuated tracks 38. Track followers 39 which are carried by a pair of vertically extending paper ejector members 40 are caused in a manner hereinafter described 45 to ride upon and be guided by said tracks 38.

The vending mechanism of my machine includes a rocker shaft 41 journaled between the side walls 22 and 23. This rocker shaft 41 is connected by linkage 42 to depending lugs 43 carried at each end of the door 14. As the door 14 is caused to pivot about its connection 18 the lugs 43 will be caused to move through an arcuated path and through the linkage 42 cause the rocker shaft to be rotated in the direction of the arrows as seen in Figs. 2 and 3.

55 The rocker shaft 41 by rods 44 is connected to a pair of pivotal members 45. These members 45 have one end pivotally connected as at 46 to stationary lugs 47 carried by the bottom wall of the cabinet 10. The opposite end of each member 45 is pivotally connected as at 48 to the bottom ends of the ejecting members 40. From the foregoing description it is readily apparent that as the door 14 is opened the rocker shaft 41 is caused to rotate in the direction of the arrows as shown in Figs. 2 and 3 and through the rods 44 will cause the members 45 to be pivoted in the direction of the arrow as seen in Fig. 3 which in turn will cause the ejecting members 40 to move vertically. Such vertical movement of the ejecting members 40 will cause the track followers 39 to follow and be guided by the tracks 38. Such movement of the ejecting members 40 will cause the forwardly positioned newspaper in the magazine i.e. the paper that is in abutting relation with the front retaining wall 21, to be raised

over and above the retaining wall 21 and be deposited on the chute 26 for gravitation thereover and out of the opening 13.

As the forwardly positioned newspaper is thus caused to be vended the flat coiled spring 35 will pull the follower 24 and chains 33 forward so as to compress the remaining newspapers in the magazine between the front retaining wall 21 and the follower 24.

In order for the ejecting members 40 to be able to easily raise and deposit the newspaper to be vended from the magazine it is desirous to relieve the compressing pressure upon the newspapers between the retaining wall 21 and the follower 24. In order to relieve this pressure I include as a part of the vending operation a follower retracting mechanism 31.

The follower retracting mechanism 31 comprises discs 49 and 50 mounted on opposite ends of the shaft 29. Mounted on the shaft 29 between the supporting members 27 and the discs 49 and 50 are ratchet wheels 51 formed as an integral part of the sprocket wheels 32. As shown in Figs. 3, 4 and 5 the discs 49 and 50 have pivotally connected to the outer face thereof arms 52. These arms 52 have their free ends connected to vertically extending levers 53. These levers 53 are in turn connected to the pivotal members 45. Mounted on the peripheral edge of each of the discs 49 and 50 is a block housing 54. Each of the block housings 54 pivotally carry pawls 55. These pawls are normally urged in one direction toward the ratchet wheels 51 by means of springs 56.

As shown in Figs. 4 and 5 the supporting members 27 have mounted on the outer face thereof a mounting block 57 which in turn supports cam levers 58. The cam levers are so positioned with respect to the ratchet wheels 51 and the pivotally carried pawls 55 that when these parts are in their normal positions the cam levers 58 will pivot the pawls 55 against the action of the springs 56 into a position where it will be out of engagement with the teeth of the ratchet wheels 51.

The arrangement of the parts of the retracting mechanism 31 is such that as the pivotal members 45 are caused to be pivoted in a clockwise direction the discs 49 and 50 through the levers 53 and the arms 52 will be caused to rotate about the shaft 29 in a likewise direction. The rotation of the discs 49 and 50 will cause the pawls 55 to move off of the cam levers 58 and into engagement with the teeth of the ratchet wheels 51. Continued movement of the discs 49 and 50 will cause the ratchet wheels 51 and the sprocket wheels 32 to be rotated in the direction of the arrows as seen in Figs. 4 and 5. Such rotation of the sprocket wheels 32 will cause the chains 33 to move in the direction of the rear of the cabinet 10 and carry with it the follower 24. Such retracting movement of the follower 24 is achieved simultaneously with the engagement of the ejecting members 40 with the forwardly positioned newspaper to be vended. As the pivotal members 45 are permitted to return to their normal position the discs 49 and 50 as well as the ratchet wheels 51 and sprocket wheels 32 will be permitted to rotate in an anticlockwise direction as seen in Figs. 3, 4 and 5 and thus return to their original position. The cam levers 58 will cause disengagement of the pawl 55 from the teeth of the ratchet wheels 51. The spring 35 will cause the follower 24 as well as the chains 33 to move forward a distance equal to the space emptied by the vended newspaper. From the foregoing it is evident that I have provided a follower 24 which will support the stacked newspapers in a compressed relation with respect to the front retaining wall 21 and which follower 24 during the operation of the vending mechanism will be caused to be retracted to release a single newspaper so that it may be easily vended.

While I have illustrated and described the preferred form of construction for carrying my invention into effect, this is capable of variation and modification without departing from the spirit of the invention. I, therefore,

do not wish to be limited to the precise details of construction set forth, but desire to avail myself of such variations ad modifications as come within the scope of the appended claims.

Having thus described my invention, what I claim as new and desire to protect by Letters Patent is:

1. A vending machine comprising a housing adapted to receive vertically related horizontally extending stacked papers to be vended, said housing having a discharge opening formed in one vertical wall thereof, a pivotal door for said opening, a paper magazine in said housing including paper supporting tracks terminating at one end into a raised retaining wall extending in a longitudinal parallel direction with respect to said door and providing a discharge chute downwardly inclined with respect to said opening, a movable follower adapted to be moved over said tracks in one direction so as to press in supporting relation against said retaining wall the papers to be vended, means for movably supporting said follower within said housing, means for moving said follower in said one direction over said tracks, a rocker shaft operatively connected to said door so as to be rotated in one direction when said door is pivoted to expose said opening in said housing, means for operatively connecting said shaft to said door, a pivotal member connected to said rocker shaft and pivoted in an opposite direction with respect to the direction of rotation of said rocker shaft when said rocker shaft is rotated in said one direction, means carried by one end of said pivotal member and movable into engagement with a folded edge of a paper to be vended and for raising the same over and above said retaining wall for gravitation down said chute and out of said exposed opening, and a retracting mechanism for moving said follower a limited distance away from said paper pressing relation with said retaining wall, said retracting mechanism including a rotatable ratchet wheel and pawl operatively connected together for moving said follower in a retracting direction with respect to said follower moving means upon pivotal movement of said pivotal member in said opposite direction with respect to the direction of rotation of said rocker shaft so as to release the papers in said magazine from pressed condition against said retaining walls as said paper engaging means are caused to be actuated so as to vend a paper from said machine.

2. A vending machine comprising a housing adapted to receive vertically related horizontally extending stacked papers to be vended, said housing having a discharge opening formed in one vertical wall thereof, a pivotal door for said opening, a paper magazine in said housing including paper supporting tracks terminating at one end into a raised retaining wall extending in a longitudinal parallel direction with respect to said door and providing a discharge chute downwardly inclined with respect to said opening, a movable follower adapted to be moved over said tracks in one direction so as to press in supporting relation against said retaining wall the papers to be vended, means for movably supporting said follower within said housing, said movable supporting means for said follower including a pair of spaced apart endless chains rotatable over corresponding spaced apart sprocket wheels, means for moving said follower in said one direction over said tracks, a rocker shaft operatively connected to said door so as to be rotated in one direction when said door is pivoted to expose said opening in said housing, means for operatively connecting said shaft to said door, a pivotal member connected to said rocker shaft and pivoted in an opposite direction with respect to the direction of rotation of said rocker shaft when said rocker shaft is rotated in said one direction, means carried by one end of said pivotal member and movable into engagement with a folded edge of a paper to be vended and for raising the same over and above said retaining wall for gravitation down said chute and out of said exposed opening, and means connected to and

movable by said pivotal member for retracting said follower a limited distance away from paper pressing relation with said retaining wall as said paper engaging means are caused to be actuated so as to vend a paper from said machine.

3. A vending machine comprising a housing adapted to receive vertically related horizontally extending stacked papers to be vended, said housing having a discharge opening formed in one vertical wall thereof, a pivotal door for said opening, a paper magazine in said housing including paper supporting tracks terminating at one end into a raised retaining wall extending in a longitudinal parallel direction with respect to said door and providing a discharge chute downwardly inclined with respect to said opening, a movable follower adapted to be moved over said tracks in one direction so as to press in supporting relation against said retaining wall the papers to be vended, means for movably supporting said follower within said housing, said movable supporting means for said follower including a pair of spaced apart endless chains rotatable over corresponding spaced apart sprocket wheels, means for moving said follower in said one direction over said tracks, a rocker shaft operatively connected to said door so as to be rotated in one direction when said door is pivoted to expose said opening

in said housing, means for operatively connecting said shaft to said door, a pivotal member connected to said rocker shaft and pivoted in an opposite direction with respect to the direction of rotation of said rocker shaft when said rocker shaft is rotated in said one direction, means carried by one end of said pivotal member and movable into engagement with a folded edge of a paper to be vended and for raising the same over and above said retaining wall for gravitation down said chute and out of said exposed opening, means connected to and movable by said pivot member for retracting said follower a limited distance away from paper pressing relation with said retaining wall as said paper engaging means are caused to be actuated so as to vend a paper from said machine, and means for guiding said paper engaging means in a predetermined direction with respect to said retaining wall as said paper engaging means raises the paper to be vended over and above said retaining wall for gravitation down said chute and out of 20 said exposed opening.
